UNITED STATES PATENT OFFICE.

FRANK E. WELLMAN, OF KANSAS CITY, KANSAS. ASSIGNOR TO THE KANSAS CITY GASOLINE COMPANY, OF KANSAS CITY, KANSAS, A CORPORATION OF KANSAS.

PROCESS OF AND APPARATUS FOR REFINING LIQUID HYDROCARBONS.

1,335,768.

Specification of Letters Patent.

Patented Apr. 6, 1920.

Original application filed June 7, 1915, Serial No. 32,704. Divided and this application filed December 30, 1915. Serial No. 69,499.

To all whom it may concern:

Be it known that I, FRANK E. WELLMAN, a citizen of the United States, residing at Kansas City, in the county of Wyandotte and State of Kansas, have invented certain new and useful Improvements in Processes of and Apparatus for Refining Liquid Hydrocarbons, of which the following is a specification, reference being had therein to the accompanying drawing.

My invention relates to the refining of hydrocarbon oils, and has for its object the production of an improved process therefor, and apparatus by which the said process may be advantageously practised.

This application is a division of my pending application Serial No. 32,704, filed June 7, 1915, and the essential feature in the present case is the separate control of a high pressure zone and a low pressure zone, in a closed circuit through which the hydrocarbon under treatment is continually passed; the hydrocarbon being heated and vaporized in the low pressure zone, superheated and cracked in the high pressure zone, the heavier constituents being then returned to the low pressure zone, and the desired lighter products being drawn off and condensed without such return. The process is rendered continuous by replacing the cracked product by oil in its primary or untreated condition in the low pressure zone.

The apparatus for practising this process includes a primary heater and vaporizer, a compressor, a superheater for cracking, condensing means, with means for fractionally separating the constituents of the cracked or partially cracked product and means for carrying back the heavier or uncracked constituents to the primary apparatus.

In the drawings attached hereto I have illustrated diagrammatically the best form of apparatus known to me at the date of filing the above mentioned parent application, for practising my invention.

In the drawings,

Figure 1 is a vertical elevation of a typical form of the apparatus, with parts in section.

Fig. 2 is a detail sectional view of one of the fractional condenser connections.

Fig. 3 is a sectional view of a form of

pump which may be employed in the return pipe line from the condenser system.

Fig. 4 is a transverse sectional view of the same.

Fig. 5 is a longitudinal sectional view of a known type of compressor which I employ.

Fig. 6 is a sectional view of a known type of pressure retaining valve for the compressor system.

As an understanding of the apparatus elements shown in Figs. 3 to 5 will aid in the understanding of my invention, I shall describe them first, a broad description sufficing as the specific structure of the said elements here shown forms no part of my invention and they may be substituted by other elements subserving the same functions. Figs. 3 and 4 are respectively longitudinal and transverse sectional views of a well known type of force pump which I use as a back trap pump for the purpose of passing a fluid from a high pressure container to a low pressure container at a given rate regardless of the difference in pressure and to hold back the pressure from the low pressure container. It consists of a pair of intermeshing gears 10^a and 10^b nested in a casing having inlet and outlet ducts 10^c and 10^d, respectively, and arranged with a snug fit of their sides and the ends of the outer gear teeth with the walls of the casing. The gears 10^a and 10^b are driven by the pinion 10^e carried by the shaft 10^f.

Fig. 5 is a longitudinal sectional view of a type of compressor selected from the prior art in which the material to be compressed is first drawn into the low pressure chamber by the piston 5^a through the inlet 5^a and the upper large valves and forced out through the lower central valves through the duct 5^b, then drawn into a tertiary pressure chamber by the plunger 5^c through the upper right-hand end valve and forced out at an increased pressure through the lower right-hand end valve to the duct 5^c, from whence it is finally drawn into a high pressure chamber by the plunger 5^d through the upper left-hand end valve and forced out at high pressure through the lower left-hand valve and conduit 5^d. The connection and arrangement of this compressor, for down discharge, is original with me but is not claimed herein.

In Fig. 1, 2 designates a container or source of supply of the hydrocarbon liquid to be treated. This is shown as a tank or boiler, provided for convenience with a furnace 1 by which heat may be initially applied to vaporize the hydrocarbon liquid if desired. From this container a pipe line 4 extends to the compressor 5, which may be of the type shown in Fig. 5, which is selected 10 from the prior art for purposes of illustration and is not in itself a part of my invention, or to be claimed herein as such. In this type of compressor, as well understood by those familiar with the art, the material 15 to be compressed is drawn in through the intake valves, which close as compression starts, whereby no back pressure is communicated through the pipe 4, but the discharge under pressure is forward only, in 20 the direction of the superheater 6. The hydrocarbon under pressure is thus forced into the upper convolution of the coil 6, which while referred to herein as a superheater, is primarily a pipe-still adapted to 25 resist high pressures.

In the form shown, the heating means for the coil 6 comprises an oil jacket 14 connected at one end through pipe 18 to a boiler 16, and at the other end through a 30 pipe 17 to a circulating pump 19 and thence to the boiler 16. This boiler is heated by a furnace 20, and contains oil which is circulated by the pump 19 through the space 15 within the jacket 14 and around the coil 35 6, returning to the boiler through the pipe 18. The pump 19 may be of any suitable type, and is not structurally illustrated, as in itself it forms no part of the present invention. The boiler 16 and its furnace 40 must be of such a type that the temperature of the oil in the boiler can be raised to a maximum of about 850 degrees Fahrenheit, and properly regulated within that limit. I may state here that in using the 45 container 2 to vaporize the primary charge of liquid hydrocarbon, I have found it advisable to limit the maximum temperature in the boiler 2 to about 650 degrees Fahrenheit, and it should be borne in mind that 50 for the essential purposes of the process I do not require and therefore do not produce pressure in the boiler 2. In using the expression hereinafter "means for vaporizing the liquid at low pressure," I mean substantially no pressure above atmospheric, 55 or a pressure extending from so measured zero to a very low maximum of a few pounds only. If the container 2 should be filled with liquid, the compressor would draw 60 over, and deliver under pressure to the coil 6, either liquid mixed with vapor, or liquid alone. I make no point herein of such delivery of liquid, as the specific arrangement I describe and shall claim herein contem- 65 plates the delivery of vapor to the com-

pressor; but a good compressor, such for example as is commonly known in the art under the name "Ingersoll-Rand," will handle oil as well as vapor, and the transmission of high pressure to the coil 6 is not 70 impaired thereby.

The lower end of the coil 6 terminates in a union 7, from which a branch pipe 8 connects with a return pipe 9, and through the back trap pump 10 to the initial source of 75 supply for the compressor 5. The pump 10 may be of any suitable type, such for example as shown in Fig. 3, with or without a separate valve of known type, the principal requirement being to maintain the full 80 head of pressure in the coil 6, without permitting any escape thereof through the pipe 9 to the tank 2. It will be sufficiently apparent to those skilled in the art, without specific description, that the pump 10 may 85 be replaced by other pressure retaining means, without departure from the spirit of my invention. The function of the pipe 9 is to drain off condensed liquid hydrocarbon which has passed through the union 90 7, without relieving the pressure at the union end of the coil 6. Any trap or back pressure device known in the art which will perform this function will satisfy the purpose of my invention.

Rising from the union 7 is a pipe 13 leading to what I shall call my fractionator, or fractional condenser. The pipe 13 terminates at a cross 22, one branch of which delivers into a pipe 24 and through a valve 31 to the final condenser 25, which may be of any ordinary and suitable type, comprising as shown, a coil immersed in cooling liquid circulated through a tank 26. The lower end of the coil 25 must obviously be provided with pressure controlling means, to prevent loss of pressure through the condenser from the pipe retort or superheater 6. Such means in the present case comprise the tank 27, provided with a pressure 1 controlling relief valve 28 and a valved drain pipe 29 through which the condensed liquid may be drawn off from the tank. The valve 28 may be of any suitable type, such as that shown in Fig. 6, which illustrates a well known device employed for pressure controlling purposes, and in which the degree of pressure at which the device will blow off is determinable by adjustment.

The valve 31 in the pipe 24, when closed cuts off the pipe 13 and the cross 22 from the condenser 25. Opening from a branch 32 in the cross is the first section 33 of the fractional condenser, having a cut-off valve 34 1 which is opened when the valve 31 is closed. The upper end of the coil or set of pipes 33 opens into a cross 22^b, connected through a pipe 24^b to pipe 36 leading to the condenser 25. Rising from the upper part of the cross 1

22^b is another stage or section 33^b of the fractional condenser, provided with a cut-off valve 34^b; and from the cross at the upper end of this second section a pipe connects it to the pipe 36, and a third section rises also cross connected, and in every respect like the preceding sections. Each of the cross connecting pipes following 24^b is provided with a valve; and it follows from this 10 construction that by proper manipulation of the valves 31 and 34, 31^b and 34^b, and so on, vapors from the pipe 13 may be caused to pass (1) direct to the condenser 25, or (2) through the section 33 and pipes 24^b 15 and 36 to the condenser 25, or (3) through both sections 33 and 33^b in series and then back through pipe 36 to the condenser 25, or (4) through all three sections 33, 33^b, and 33^c, in series and then on to the condenser 25, 20 or (5) through still further sections of the fractional condenser, if such there be, and then on to condenser 25.

It will be observed that from the highest point of the fractional condenser system to 25 the lowest point of the drainage pipe 9, there is a continuous fall. This is in order to completely drain back through all the pipes and the union 7, all liquid products 30 condensed in the pipes. In Fig. 2 I have shown on a larger scale a section of the cross 22 and connected parts. It will be observed that in each cross a thermometer 38 is inserted, whereby the temperature of the vapor may be continuously observed as it 35 rises. All of the fractional condenser units 33, 33^b, etc., are preferably air cooled, and being exposed to the atmosphere, are kept at substantially constant external temperature.

The operation of the apparatus thus described is as follows: The liquid hydrocarbon or other compound to be treated is placed in the primary container or vaporizer 2, where it may be heated to produce vaporization. The composite vapor is then drawn 45 off through the pipe 4 by the compressor 5 and delivered into the coil of the pipe-retort 6 under pressure, which is controllable as to its degree in several ways. It may be controlled first by regulating the amount of 50 power delivered to the compressor from the engine or other prime mover; or second, by regulating the percentage of power actually expended in compression in the pipe-retort 6, or in other words the percentage of efficiency of the compressor; or third, by means 55 of the valves 31—34, 31^b—34^b, etc.; or fourth, by the valve 28; or fifth and finally, by any or all of these in combination. It will be particularly observed that the production and regulation of the pressure in 60 the pipe-retort 6 are thus rendered entirely mechanical, and are entirely independent of and extraneous to the heating system, by which I mean the agencies for communicating heat energy to the hydrocarbon under

treatment in any stage of the process. On the other hand, it is to be observed with equal particularity that the production and regulation of heat as a separate factor, in the hydrocarbon contained within the pipe-retort 6 are by means of agencies controllable quite independently of the compression system. The simple and most obvious method of regulating the heat is of course by regulating the temperature in the boiler 70 16, and for that purpose regulating the intensity of the flame in the furnace, or the percentage of efficiency of the same in any well understood manner. Any heating effect due to compression, and any compression effect due to heat, are to be regarded as incidental, and not affecting the independence of control constituting the characteristic feature of my invention.

The temperature in the pipe-retort 6 having been raised to a point preferably between 750 and 850 degrees Fahrenheit, and suitable compression effected by means of the compressor 5, the molecular structure of the vapor is broken down or "cracked" to 85 separate the elements into their several groups. This effect is due to the molecules being compressed in close relation and at the same time caused to move rapidly because of the high temperature and results in a reduction from groups having higher to groups having lower specific gravity, the high and controllable pressure on the superheated vapor also preventing excessive decomposition of the compound by the high 90 temperature, and serving to hold the compound in the desired series.

After cracking, and when the vapor has been driven downwardly through the coil 6, it passes into the pipe 13 and is delivered into the fractional condensers or directly into the final condenser according to the condition of the valves 31—34. If valve 34 is closed and valve 31 open, the vapor passes into the condenser 25 and after condensation into the tank 27 or through the pipe 29 as may be desired. Excess of pressure is relieved, and waste gases of a non-condensable nature are blown off, through the valve 28. Condensed drainage and residual liquid from the pipe 13 pass through the pipes 8 and 9 and back in the system to a primary source of supply shown as the tank 2, but which may be any one of the primary containers if a plurality of the same be 105 employed.

If the valve 31 be closed and the valve 34 be open, the vapor will pass through the pipes 33, rising to the cross 22^b, vapor remaining at that point passing over through 110 the pipe 36 to the final condenser 25, while liquid condensed in the pipe 33 will drain down by gravity throughout the length thereof, through the cross 32 and the pipe 115 13 to the union 7 and so to the return pipes 120 130

8 and 9. If a series of lower specific gravity be desired, one or more additional sections 33^b and 33^c are cut in by manipulation of their valves 31^b—34^b, etc. The lower the 5 specific gravity desired, the more sectional units should be cut in, until only the desired vapors will ascend and pass over the final cross connection 24 to the pipe 36 and condenser 25; while the condensation liquid 10 containing all units of higher specific gravity will pass back through the pipe 13 and the return pipe 9 to the initial vaporizer, to be re-distilled and re-cracked, by unbroken continuation of the process.

15 I am aware that fractional condensation has been proposed, but not in the manner nor by the means which I disclose, nor for selective purposes and with selective functions as herein set forth, nor with regulating 20 means, nor in combination with cracking means or a superheater of the type and for the purpose herein set forth. I shall therefore claim broadly all the features which I consider to be new and original with 25 me, including those named. I shall also claim broadly as a characteristic feature of my invention, the combination described of a compressor and a pipe-retort, as well as independently controlled compressing and 30 heating means.

It is to be understood that various changes in matters of detail may be made, and other forms of apparatus may be substituted, in and for the apparatus shown and described 35 herein, without departing from the spirit of my invention. All such changes and modifications are contemplated by me, and are intended to be included within the scope of the following claims.

40 Having thus described my invention what I claim and desire to secure by Letters Patent is:

1. Apparatus for refining liquid hydrocarbons by continuous process comprising a 45 complete circulating system which includes the following elements connected together in tandem: (a) a container or source of supply vaporizing hydrocarbons at low pressure, (b) a compressor adapted to draw 50 in hydrocarbon vapor at low pressure from the source of supply, and then force it forward in the system, under compression, (c) a retort adapted to resist very high pressures receiving the hydrocarbon vapors under 55 compression from the compressor, (d) a return pipe line leading from the delivery side of the retort back to the source of supply, (e) means in said pipe to permit continuous circulation in the system through 60 elements (a), (b), (c), and (d), but adapted to hold back the pressure in the retort; and means for heating the retort and its contents to a very high temperature while under pressure, and condensing means connected to the

circulating system between the retort and 65 the return pipe line, adapted to continuously receive and condense predetermined constituents of the product in course of circulation through the system after exposure in the retort to heat and pressure with consequent cracking of the vapor.

2. Apparatus for refining liquid hydrocarbons by continuous process comprising a complete circulating system which includes the following elements connected together 75 in tandem in the order named: (a) a container or source of supply to vaporize hydrocarbons under low pressure, (b) a compressor adapted to draw in hydrocarbon vapor from the source of supply and force it forward in the system, under compression, (c) a continuous pipe-retort adapted to resist very high pressures, receiving the hydrocarbon vapor under compression from the compressor, (d) a return pipe line leading from 80 the delivery side of the retort back to the source of supply, (e) means in said pipe to permit continuous circulation in the system through elements (a), (b), (c), and (d), but adapted to hold back the pressure in the retort; and means for heating the retort and its contents to a very high temperature while under pressure, and condensing means connected to the circulating system between the retort and the return pipe line, adapted to 85 continuously receive and condense predetermined constituents of the product in course of circulation through the system after exposure in the retort to heat and pressure, with consequent cracking of the vapor.

3. Apparatus for refining liquid hydrocarbons by continuous process comprising a complete circulating system which includes the following elements connected together 90 in tandem in the order named: (a) a source of supply comprising means for vaporizing hydrocarbons under low pressure, (b) a compressor adapted to draw in hydrocarbon vapor from the source of supply and force it forward in the system under compression, (c) a retort adapted to resist very high pressures, receiving the hydrocarbon under compression from the compressor, (d) a return pipe line leading from the delivery side of the retort back to the source 95 of supply, (e) means in said pipe to permit continuous circulation in the system through elements (a), (b), (c), and (d), but adapted to hold back the pressure in the retort; and means for heating the retort and its contents to a very high temperature while under pressure, and selective means connected to the circulating system between the retort and the return pipe line, said means adapted to select and pass out of the system for 100 final condensation predetermined constituent portions only of the product of cracking in the retort, and acting to return the resi-

due of the product to the return pipe line for continued inclusion in the circulation and further exposure to the several steps in the process.

5 4. Apparatus for refining liquid hydrocarbons comprising a source of supply of the hydrocarbon, means to vaporize the hydrocarbon, a retort adapted to resist high pressures, means connected between the source 10 and the retort adapted to take in hydrocarbon vapor at low pressure from the source and deliver the same under compression to the retort, a source of power for said compressing means, means independent of the 15 compressing means and of its source of power, to heat the retort and its contents while under high pressure, to a temperature high enough to break down the molecules of the hydrocarbon, selective means connected to receive the product from the retort and adapted to separate the different constituents of said product, and a plurality of pipe connections to carry off the separated products from said selective means, said 20 selective means being arranged to receive the product in a constantly upward movement therethrough from near the bottom of the retort.

5. Apparatus for refining liquid hydrocarbons comprising a source of supply and means for vaporizing hydrocarbons under low pressure, a retort adapted to resist high pressures, means connected between said vaporizing means and the retort adapted to 30 take in hydrocarbon vapor at low pressure from said means and deliver the same under compression to the retort, a source of power for said compressing means, means independent of the compressing means and of its source of power, to heat the retort and its contents while under high pressure, to a temperature high enough to break down the molecules of the hydrocarbon, selective means connected to receive the product from 35 the retort and adapted to separate the different constituents of said product, and a plurality of pipe connections to carry off the separated products from said selective means, one of said pipes leading and connected to the source of supply, with means 40

therein to prevent loss of pressure from the retort through said pipe.

6. Apparatus for refining liquid hydrocarbons by continuous process comprising a complete circulating system including in the 55 circuit a low pressure inclosure or zone and a high pressure inclosure or zone, means for heating and vaporizing the compound in the low pressure zone, means for superheating the compound in the high pressure zone, and 60 means for passing the hydrocarbon compound from the low pressure zone to the high pressure zone and from the high pressure zone to the low pressure zone while maintaining said zones isolated from each other, means for separating the heavy and light constituents of the compound in the high pressure zone before condensation of the light constituents, and means out of said circuit for condensing the light constituents. 65

7. The process of refining liquid hydrocarbon which consists in forcing the hydrocarbon compound repeatedly through a closed circuit including a high pressure zone and a low pressure zone while maintaining 75 the portions in the different zones mechanically isolated; heating and vaporizing the same in the low pressure zone; superheating, cracking and condensing in the high pressure zone, returning to the low pressure 80 zone the heavier constituents of the treated product and drawing off and condensing the desired product.

8. The process of refining liquid hydrocarbon which consists in forcing the hydrocarbon compound repeatedly through a closed circuit including a high pressure zone and a low pressure zone while maintaining 85 the portions in the different zones mechanically isolated; heating and vaporizing the same in the low pressure zone; superheating, cracking and condensing in the high pressure zone, returning to the low pressure zone the heavier constituents of the treated 90 product, drawing off and condensing the desired product, and supplying fresh compound in the low pressure zone. 95

In testimony whereof I affix my signature.

FRANK E. WELLMAN.
